ADJUSTABLE KEY FOR USE WITH LOCKS IN
WHICH THE TUMBLERS ARE MOVABLE
PARALLEL TO THE AXIS OF THE PLUG

Carlos Jaramillo Borda, San Jose, Costa Rica

Application April 2, 1948, Serial No. 18,668

5 Claims. (Cl. 70—411)

1

The present invention relates to an adjustable key for use with locks of the type in which the paths of movement of the tumblers are parallel to the axis of the plug.

There are many instances in which it is advantageous to provide a single key which is capable of opening a plurality of locks. In most of these instances, it has been customary to provide a master or "skeleton" key which is correlated to all of the locks to be opened. This expedient has the disadvantage that an unscrupulous person may come into possession of the master key, and thus be able to gain access to all of the compartments or rooms which are locked. Even though such an unscrupulous person might have temporary rather than permanent access to the master key, he could have a duplicate master key manufactured, in which case the eventual result might be even worse because of the fact that the existence of a duplicate master key would be unknown to the appropriate individuals.

Even though a key may be designed to open a single lock or a small group of locks, there exists the possibility that the key may come into the possession of unauthorized persons. In that event, a conventional key can be used by the unauthorized person for illegal or illegitimate purposes.

The present invention provides a key which is adjustable. Several hundred thousand adjustments are possible but only one of those adjustments will permit the key to open a particular lock. A key constructed in accordance with the present invention may be adjusted to open any of a large number of locks by any authorized person having knowledge of the appropriate adjustment for each lock. When the key is intended for use with a single lock, it is possible to move certain elements of the key out of appropriate adjustment and even though such key may come into the hands of unauthorized persons there is an almost infinitesimal possibility that such persons will be able to appropriately adjust the key for opening the lock.

The primary object of my invention is to provide an adjustable key for use with locks in which the tumblers are movable in paths parallel to the axis of the plug.

Another object of my invention is to provide an adjustable key for use with locks of the type described which can be easily and quickly adjusted to open a lock or locks by any person authorized to do so and having knowledge of the proper adjustment.

A further object of the invention is to provide

2

such a key which is small and rugged, and which can be manufactured and sold at a reasonable cost.

For a more complete understanding of my invention, reference is made to the accompanying drawings which illustrate preferred forms of my invention, and in which:

Figure 1 is a front elevation view of a lock of the type with which the key is intended to be used;

Fig. 2 is a transverse sectional view of the lock shown in Fig. 1, and also showing, in cross-section, a key constructed in accordance with one form of the present invention, the key being illustrated in position for insertion into the lock;

Fig. 3 is a fragmentary sectional view of a lock and key which illustrates the manner in which the key actuates the tumblers of the lock to permit rotation of the plug.

Fig. 4 is a greatly enlarged view, partly in side elevation and partly in section, of a key constructed in accordance with one form of the present invention:

Fig. 5 is an end elevation view of the front or forward end of the key;

Fig. 6 is a sectional view looking in the direction of the arrows along the line 6—6 of Fig. 4;

Fig. 7 is a perspective view of one of the pin and block elements which are used with the form of key illustrated in Fig. 4;

Fig. 8 is a perspective view of a clamp used to retain the pin and block elements in adjusted position relative to the body member of the key;

Fig. 9 is a perspective view of one of the stops or filler members used with the key; and

Fig. 10 is a fragmentary sectional view illustrating a modified form of lock and a correspondingly modified form of key.

For purposes of illustration only the lock is shown as incorporated in a member 11, which may be a door, the front of a desk drawer, or any other appropriate member which it is desired to lock in a particular position. The lock includes a generally cup-shaped housing 12 which is shown as recessed into the member 11. The plug of the lock is designated by the reference numeral 13, and is rotatable within the housing 12 when certain tumblers, which are hereinafter described, are in appropriate positions. The plug 13 is provided with a stem 14 which carries at one end a cam or lever 15, which controls the bolt of any appropriate locking mechanism which it is considered unnecessary to show in the drawings. An annular ring 16 is secured to the housing 12 and the member 11 by means of screws or other

appropriate fastening means 17 in the manner clearly shown in Fig. 2. The inner edge of the annular ring 16 overlies the outer edge of the plug 13 to prevent intentional or accidental removal of the plug from the lock.

When the plug 13 occupies the position illustrated in Fig. 2, the lever or cam 15 is in position to retain the bolt of the lock in locking position. The plug 13 is prevented from rotating from this position by the tumblers which are movable in paths which are parallel to the axis of the plug. The lock illustrated is provided with four tumblers, but it will be obvious as the description proceeds that a greater or lesser number of tumblers may be employed. These tumblers may be, and preferably are, of different lengths. The tumbler 18 in Fig. 2 is illustrated as considerably longer than the tumbler 19. The tumblers 18 and 19 are backed by compression springs 20 which are positioned in wells 21 in the housing 12. The outer ends of the tumblers 18 and 19 abut against the heads 22 and 23 of pins 24 and 25, respectively. The combined lengths of the tumbler 18 and the head 22 is illustrated as being equal to the combined lengths of the tumbler 19 and the head 23. Plug 13 may be rotated to release or retract the bolt of the lock only while the tumblers 18 and 19 are in the positions illustrated in Fig. 3. It will be obvious from an inspection of Fig. 3 that the key has depressed the tumbler 18 into its well 21 a distance greater than has been the case with the tumbler 19.

The foregoing brief description is sufficient to explain the manner of operation of the lock. Although there have been described the movements of only two tumblers and pins, it should be understood that any additional tumblers or pins which may be embodied in the lock will function in a similar manner. It is preferable that in any given lock, no two of the tumblers are of the same length, thus making it necessary to depress the pins which cooperate with the tumblers to different extents to permit rotation of the plug of the lock.

The key illustrated in Figs. 2 to 9, inclusive, comprises a generally cylindrical body member 26 having passages 27 extending inwardly from one end thereof. The pins 30 are arranged to be positioned in axial alignment with the pins of the lock in the manner best illustrated in Figs. 2 and 3. Channels 28 are formed in the walls of the body member 26, and these channels extend inwardly to the passages 27. The channels 28 extend entirely to the leftward end of the body member 26 as that member is viewed in Fig. 4. These channels are arranged to receive blocks 29, and the passages 27 receive pins 30 which are carried by the blocks 29, preferably as integral parts thereof. The blocks 29 and the channels 28 are of the configuration best illustrated in Figs. 6 and 7. The blocks 29 are slidable in the channels 28 longitudinally of the body member 26 and the pins 30 move within the passages 27 when the blocks 29 are moved. It is thus possible to adjust the positions of the ends 31 of the pins 30.

A clamp is provided for each of the blocks 29 for the purpose of clamping those blocks against the side walls of the channels 28 to prevent longitudinal movement of the blocks 29 and the pins 30 relative to the body member 26. One such clamp is best illustrated in Fig. 8 and comprises a pair of parallel clamping members 32 and 33, which are connected together by means of a T-shaped lever 34. One arm of the T-shaped lever

34 is provided with righthand threads while the opposite arm is provided with lefthand threads. The clamp is positioned within a notch in the block 29. This notch has downwardly diverging walls as best illustrated in Figs. 4 and 7, and the ends of the clamping members 32 and 33 are complementarily diverging. It will be apparent that when the block 29 and its clamp are positioned in one of the channels 28, the lever 34 may be rotated in a direction to cause spreading of the clamping members 32 and 33 into clamping engagement with the side walls of the channel 28. I have shown the block 29 provided with recesses 35 and 36 to permit greater movement of the lever 34 and to enable that lever to be positioned below the surface of the key after appropriate adjustments have been made.

Each of the channels 28 is provided with a stop or filler block 37, which is best illustrated in Fig. 9. The body member 26 is externally threaded at its leftward end, as viewed in Fig. 4, for reception of an internally threaded cap 38 which carries a handle member 39. The stops or filler members 37 are also externally threaded at one end, as indicated by the reference numeral 40, and these external threads may cooperate with the internal threads of the cap 38. It will thus be apparent that the stops 37 may be adjusted longitudinally of the channels 28 when the cap 38 is removed from the body member 26. It will also be apparent that the stops 37 will be retained in any desired position upon replacement of the cap 38 due to engagement of the internal threads of the cap with the threads 40 on the stops. The stops or filler members 37 serve to limit the extent of movement of the blocks 29 in one direction, and they act as a filler to give a rounded contour to the key.

A scale 41 is positioned on the body member 26 between each of the channels 28, and the surface of each block 29 is provided with a vernier scale 42. The scale 41 and the vernier scale 42 permit exact positioning of the blocks 29 and the pins 30.

The handle member 39 or the body member 26 may carry suitable indicia for indicating proper angular orientation of the key relative to the lock.

In the form of key illustrated in Figs. 2 to 9, inclusive, the ends 31 of the pins 30 never project beyond the corresponding end of the body member 26. It is therefore necessary for the pins of the lock, such as those designated by the reference numerals 24 and 25, to protrude from the plug 13. In the form of lock and key illustrated in Fig. 10, the ends 31a of the pins 30a protrude beyond the end of the body member of the key. In this form of the invention, the pins 24a and 25a of the lock may be recessed within the plug 13a at all times. The lock and key arrangements shown in Fig. 10 are in all other respects identical with the form above described.

The blocks 29 and the pins 30 must be individually adjusted to proper positions to enable the key to be used to open any particular lock. The lock may be easily disassembled to permit interchanging of the sets of tumblers and their co-operating pin heads. Thus, the key setting required for the individual lock may be changed from time to time. The key may be used to open the lock while properly adjusted, and after use the proper adjustment may be destroyed merely by moving one or more of the blocks 29. The lock can then be opened only by proper readjustment of the key. When a user desires

to exercise abundant caution, he may destroy the proper adjustment of the key by moving one or more of the blocks 29, and he may then make the readjustment of the key more difficult by altering the positions of the stops 37 so that these stops prevent proper positioning of one or more of the blocks 29. A single key may be used to open a large number of locks, providing the person in possession of the key is familiar with the proper adjustments of the key for each lock. The tumblers and their cooperating pin heads must be in exactly the right positions to permit rotation of the plug, and this permits the use of tumblers differing in lengths by small increments. An extremely large number of combinations of tumblers and pin heads may thus be used with any given lock. The possibility of using such a large number of combinations of tumblers increases tremendously the number of possible adjustments of the key. Since there can be only one proper adjustment, the possibility that any unauthorized person may use the key becomes almost nonexistent.

The illustrated forms of my invention are to be regarded as exemplary only and various changes and modifications may be resorted to without departing from the broader aspects of the invention as defined by the following claims.

Having thus described my invention, I claim:

1. An adjustable key for use in locks of the type in which a plurality of tumblers extend parallel to the axis of the plug, said key comprising

5

30

ing a body member defining a plurality of parallel passages extending inwardly from one end thereof, said passages being arranged for axial alignment with corresponding tumblers of the plug of the lock with which the key is to be used, channels in the side walls of said body member extending inwardly to said passages, blocks slideable in said channels and having pins which extend into said passages for engagement at their forward ends with tumblers of the lock, and laterally expandable clamps carried by said blocks for clamping engagement with the walls of said channels to prevent movement of said blocks and pins relative to said body member.

2. An adjustable key as described in claim 1, in which said blocks are provided with notches and said clamps are positioned in said notches.

3. An adjustable key as described in claim 1, in which said blocks are provided with notches and each of said clamps comprises a pair of parallel members positioned in said notches and having means for forcing said members into engagement with opposite walls of said channels.

4. An adjustable key as described in claim 1, in which said pins extend entirely through said passages and protrude from the end of said body member.

5. An adjustable key as described in claim 1, in which said pins terminate in said passages.

CARLOS JARAMILLO BORDA.
